UNITED STATES PATENT OFFICE.

WILLIAM H. ALLEN, OF MOMENCE, ILLINOIS, ASSIGNOR OF ONE-THIRD TO ERNEST A. KRAMER, OF GRANT PARK, ILLINOIS.

BRICK-CARRIER.

1,308,021.

Specification of Letters Patent.

Patented July 1, 1919.

Application filed May 10, 1917. Serial No. 167,781.

To all whom it may concern:

Be it known that I, WILLIAM H. ALLEN, a citizen of the United States, residing at Momence, in the county of Kankakee and State of Illinois, have invented certain useful Improvements in Brick-Carriers, of which the following is a specification, reference being had therein to the accompanying drawing.

10 The invention relates to a loading and unloading device, and more particularly to the class of carriers for handling bricks.

The primary object of the invention is the provision of a device of this character wherein a number of bricks can be transferred from a stack or kiln to a car or vice versa, thereby eliminating the manual handling of said bricks for this purpose.

Another object of the invention is the provision of a device of this character wherein bricks arranged in a plurality of rows in a stack can be firmly grabbed in a single operation for the transfer thereof by the device to transport the bricks from one point to another and all of the bricks held by the device may be simultaneously released at the point desired.

A further object of the invention is the provision of a device of this character wherein the construction thereof is novel in form so as to enable a number of bricks or other like articles to be transferred thereby in a single operation with minimum labor and time.

35 A still further object of the invention is the provision of a device of this character which is simple in construction, readily and easily operated and inexpensive in manufacture and installation.

40 Other objects will be in part obvious and in part hereinafter set forth.

The invention accordingly consists in the features of construction, combination of elements and arrangement of parts which will be exemplified in the construction herein-after described, and the scope of the application of which will be indicated in the appended claims.

In the accompanying drawings:

50 Figure 1 is a top plan view of a carrier constructed in accordance with the invention;

Fig. 2 is a side elevation thereof;
Fig. 3 is an end elevation;

Fig. 4 is a fragmentary detail perspective view of the gripping jaws of the device;

Fig. 5 is a perspective view of one of the actuating shafts of the device.

Similar reference characters indicate corresponding parts throughout the several views of the drawings.

Referring to the drawings in detail, the device comprises a frame A including a plurality of spaced parallel bars 10 which extend longitudinally of the frame and end bars 11 to which are riveted or otherwise secured the longitudinal bars 10, the longitudinal bars being slightly upwardly bowed for giving an arched formation to the frame. Secured to the under faces of the end bars 11 transversely thereof are spaced parallel guide cleats 12 for the slidable mounting of gripping members hereinafter fully described. The gripping members each comprises a substantially L-shaped jaw 13 which is of a length equal to the length of a brick and secured to the upper face of the flange 14 of said jaw 13 are slides 15 which engage the cleats 12 adjacent thereto for the slidable mounting of the jaw on the frame, the cleats 12 and slides 15 being formed with beveled contacting edges 16 so that when the slides 15 are engaged with the cleats 12 there is no possibility of the separation of the jaw 13 from the frame. It is, of course, understood that the jaws 13 are arranged at opposite sides of the frame A and cooperate in pairs with each other for the gripping of a row of bricks to be transferred from one point to another by the device in a manner presently described.

Rising from the end and intermediate longitudinal bars 10 of the frame A are supports 17 on which are detachably mounted bearing blocks 18 in which are journaled a pair of spaced parallel actuating shafts 19, the intermediate support 17 being notched at 20 to accommodate the shafts 19 at this point. Upon these shafts 19 are fixedly mounted crank arms 21 to which are pivoted at 22 links 23, the same being also pivoted at 24 to plunger rods 25, which are slidably mounted in upturned ears or lugs 26 formed on stationary arms 27 which are fixed to the jaws 13 medially thereof. Surrounding the rods 25 are coiled compression springs 28 which have their outer ends working against adjusting nuts 29 threaded on the outer ends

of the rods 25, and on the turning of the nuts 29 the compression of said springs 28 can be varied. On rotation of the shafts 19 in one direction the plunger rods 25 are moved outwardly and in this manner the jaws 13 are free to spread apart for their release from clamping engagement with bricks or like articles which may have been clamped between them. On actuating the shafts 19 in the reverse direction there is exerted a compression upon the springs 28 as the rods 25 are moved inwardly, and these springs when compressed, will act upon the arms 27 on the jaws, thereby moving said jaws 13 at opposite sides of the frame toward each other for the clamping between them of bricks or the like.

Mounted on one of the shafts 19 is a throw lever 30 which carries a latch blade 31 adapted for engagement with a toothed segment 32 fixed to and rising from the frame at one end thereof, and in this manner the lever 30 can be held fast in its thrown position and freed when moved in one direction for the clamping engagement of the jaws 13 with rows of bricks to be transferred by the carrier from one point to another.

Mounted on the shafts 19 are meshing cog gears 33 so that on actuating one of the shafts in one direction the other shaft will be operated or actuated in the opposite direction, and in this manner the jaws are moved in unison to clamping or unclamping positions.

Fixed to the frame A and rising therefrom are suspension legs 34 which are fixed to a crown or head plate 35 which constitutes a turntable for the carrier, the plate being superimposed upon a disk 36 which has fixed thereto angle irons 37 adapted for connection with a trolley, crane or other movable support so that the carrier can be conveyed from one point to another in the transferring of bricks or the like from a kiln to a car or vice versa. The head 35 is rotatably supported upon the disk, the head being formed with a central opening 38 through which are passed the fasteners 39 connecting the angle irons 37 with the disk 36, the angle irons 37 being spaced the thickness of the head 35 from said disk through the medium of spacer washers 40 which surround the fasteners and are interposed between the disk 36 and said angle irons.

The carrier is suspended from the trolley in any approved manner and can be readily turned or rotated for the convenient handling of its load with despatch.

In the operation of the carrier the same is brought into a position above the stack of bricks, which latter are arranged in rows, it being understood, of course, that the jaws 13 of the carrier have been separated the required distance apart and on the lowering of the carrier into gripping position the

jaws will assume a position for the clamping of a number of bricks in each row therebetween, and this is accomplished by actuating the lever 30 in one direction so that the jaws will move toward each other and thereby gripping the bricks therebetween. When the bricks have been clamped in the carrier the same are transferred thereby from the stack to a car.

It will be obvious that the carrier is adaptable for the transfer of other articles of block formation or said carrier can be used for the gripping of beams or other like material for the transfer of the same from one point to another.

From the foregoing description, taken in connection with the accompanying drawings, the construction and operation of the herein described brick carrier will be readily apparent and, therefore, a more extended explanation has been omitted.

Having thus described my invention, I claim:

1. In a device of the character described, a frame of substantially arched conformation, guides on the under face of said frame and on opposite sides of the peak of the arch of the latter, a plurality of gripping jaws provided each with slides engaging the said guides, a hand lever pivotally mounted on the frame, means for engagement by the hand lever to lock it in various angular positions, and positive connections between the hand lever and the gripping jaws whereby opposed jaws may be moved toward or away from each other so as to effect a gripping operation on a row of bricks or the release of such row after having once been gripped.

2. In a device of the character described, a frame of substantially arched conformation, guides on the under face of said frame and on opposite sides of the peak of the arch of the latter, a plurality of gripping jaws provided each with slides engaging the said guides, a hand lever pivotally mounted on the frame, means for engagement by the hand lever to lock it in various angular positions, a pair of positively connected parallel shafts operatively connected with the hand lever, connections between the shafts and the gripping jaws so that movement of the lever may cause the jaws to be moved toward and away from each other, and means for suspending the frame so that it may be turned angularly.

3. An apparatus of the character described, comprising a frame, a plurality of gripping members movably supported on the frame to coact in pairs with each other, means for actuating said members to move the same into and out of gripping position, resilient means coacting with the last named means and tending to normally force the said members into gripping position, and means for locking the first named means

whereby the said gripping members will be positively retained in either gripping or non-gripping position.

4. An apparatus of the character described, comprising a frame, a plurality of gripping members movably supported on the frame to coact in paths with each other, means for actuating said members to move the same into or out of the gripping position, resilient means coacting with the last

named means and tending normally to force said members into gripping position, means for locking the first named means so that the gripping members will be positively retained in either a gripping or a non-gripping position, and suspension means for the frame to permit the latter to be raised and rotated. 15

In testimony whereof I affix my signature.

WILLIAM H. ALLEN.
